his Attorney.

Patented Feb. 27, 1923.

UNITED STATES PATENT OFFICE.

MORRIS J. BERG, OF ST. PAUL, MINNESOTA.

FOOT FOR SEWING MACHINES.

Application filed April 4, 1921. Serial No. 452,382.

To all whom it may concern:

Be it known that I, MORRIS J. BERG, a citizen of Poland, residing at St. Paul, in the county of Ramsey and State of Minnesota, have invented new and useful Improvements in Feet for Sewing Machines, of which the following is a specification.

Sewing machines in common use for heavy service employ four interchangeable feet to guide and hold the fabric beneath the needle. These feet, viz, a plain solid foot, a plain swinging foot, a solid gauge foot and a swinging gauge foot are used during different stages of work and must 10 frequently be exchanged one for another during the process of making or repairing a garment. Such interchange of parts necessitates readjustment and results in loss of much valuable time.

It is my object to save inconvenience and loss of time by providing an efficient foot to take the place of the four feet formerly used.

A further object of my invention is to 25 provide a single foot which may be quickly adapted to do the work of a solid or swinging, gauge or plain foot.

Other objects of my invention will appear and be more fully pointed out in the 30 following specification and claims.

The drawings forming part of this specification illustrate what I at present believe to be the best form of my device but it will be understood that modifications are possible within the spirit of my invention.

Referring to the accompanying drawings Figure 1 is a perspective view of my improved foot mounted on a sewing machine of common type; Fig. 2 is a plan view of 40 the same detached from the machine; Fig. 3 is a side elevation of the same; Fig. 4 is an end view of the same; Fig. 5 is a section taken on the line 5—5 of Fig. 3; Fig. 6 is a detail perspective view of the detachable 45 prong and Fig. 7 is a similar view of the gauge which may be substituted for the detachable prong shown in Fig. 6.

My improved foot is designed to be fastened in the usual manner to the squared 50 lower end of the spindle 1 of the sewing machine by means of a screw 2 which engages a channel 3 on the sides of a slot 4. This channel 3 is adapted to receive the squared lower end of the spindle 1 and is 55 formed integral with a shank 5 of the foot. A central body portion 6, integral with the

shank 5, projects at right angles to said shank to form a support for the lower or swinging part 7 of the foot. The part 7 is formed with a pair of upwardly projecting 60 ears 8 and a rigid prong 9 and its lower surface is smooth to form a bearing for the fabric to be sewed. The ears 8 are tiltably connected to the body 6 by means of a pin 10 which passes through suitable perforations in said ears and body, and a set screw 11 in a tapped hole in one of the ears 8 is provided to engage the body 6 and hold said body and the part 7 in the full line position shown in Fig. 3 when it is desired to use 70 the foot in its rigid or solid capacity. The inner end of the screw 11 is formed to enter a suitable recess in the body 6 when the lower part 7 is in the full line position shown in Fig. 3. A stop comprising a lug 75 12 on the part 7 and a coating lug 13 on the body 6 is provided to limit the tilting motion of the part 7 on the pin 10 when the foot is used in its swinging capacity.

A removable prong 14 similar to but 80 slightly shorter than the prong 9 is formed with a tongue 15 which may be inserted in a suitable groove in the part 7 beneath the ears 8. When thus inserted the prong 14 is held in place by a pair of springs 16 mounted 85 on the ears 8 and a flange 17 on the end of said tongue which engages the outer edge of the rigid prong 9 (see Figs. 5 and 6). When desired, a gauge 18 may be substituted for the rigid prong 14 by removing 90 said prong and inserting the end 19 of said gauge in the groove beneath the spring 16.

Operation.

In operation my improved foot is mounted 95 on the spindle 1 of the sewing machine by means of the screw 2 as described above. If a plain solid foot is needed the prong 14 is mounted adjacent to the prong 9, as shown in Figs. 2, 3 and 4, and the screw 11 is 100 tightened so as to fasten the lower part 7, carrying the prongs 9 and 14, to the body 6. This holds the foot in the position shown in the full lines in Figs. 2, 3 and 4. When a plain swinging foot is needed the screw 11 is 105 loosened, and, the prong 14 being in place beside the prong 9, the lower part 7 is free to tilt on the body 6 to permit the foot to pass over obstacles such as heavy seams and the like. To adapt the foot for use with 110 the gauge 18, it is only necessary to remove the prong 14, against the action of the

spring 16, and to substitute the gauge therefor. The gauge foot may be made either swinging or solid by loosening or tightening the screw 11 as described above.

5 Having described my invention what I claim as new and desire to protect by Letters Patent is:

1. In a device of the class described a shank formed with a body extending at an angle therefrom, a prong formed with upwardly projecting ears tiltably connected to said body, said ears being formed with recesses adapted to receive a second prong or a gauge, a second prong formed with a short tongue adapted to be inserted in said recess and means for removably holding said prong or gauge within said recess.

2. In a device of the class described, a shank having a body extending at an angle therefrom on its lower end, a prong formed with upwardly projecting ears tiltably connected to said body, said ears being formed with recesses adapted to receive a second prong or a gauge, a second prong formed with a short tongue adapted to be inserted in said recess, means for removably holding said prong or gauge within said recess and a screw arranged to be manipulated to rigidly secure said first mentioned prong to said shank.

30 In testimony whereof, I have hereunto signed my name to this specification.

MORRIS J. BERG.
